UNITED STATES PATENT OFFICE.

WILLIAM DUBILIER, OF NEW ROCHELLE, NEW YORK, ASSIGNOR TO RADIO PATENTS CORPORATION, OF NEW YORK, N. Y., A CORPORATION OF NEW YORK.

ELECTRIC FLASHER DEVICE.

Application filed October 25, 1926. Serial No. 144,011.

This invention relates to improvements in controlling devices, especially controlling devices of the flasher type as described in my co-pending application, Serial No. 134,926, Sept. 11, 1926.

An object of this invention is to provide a flasher of simplified structure permitting convenient assembly and eliminating all need for riveting or otherwise joining working parts together.

The nature of the invention is set forth in the following description and accompanying drawings, which show a form in which my invention can be embodied, but the disclosure is illustrative only, and I may change the details of construction without departing from the principle of the invention or exceeding the scope and meaning of the terms of the appended claims.

On the drawings, Figure 1 is a transverse section of a device according to my invention.

Figure 2 is a top view of one of the parts of said device.

Figure 3 is a side view of the same part.

Figure 4 is a plan view of a thermal element used in said device.

Figure 5 shows a plan view of the body of the device, which forms an insulating support for the members by which the desired operation is effected.

Figure 6 is a plan view of an alternative arrangement for a device according to my invention.

Figure 7 is a cross section of this alternative device along the line 7—7 of Figure 6, and

Figure 8 is a cross section of the device according to Figure 6 along the line 8—8.

The device is particularly adapted for flashing or periodically interrupting an electric circuit, such as the circuit of an incandescent lamp. It is of such a form and size that it can be readily inserted in the usual

type of lamp socket. In the insulating body or base 1, which is preferably disk-shaped, there are two depressions 2 on opposite sides or faces, and an opening 3 connecting the depressions 2. In one of said depressions is mounted a bimetallic thermal element 4 with a contact point 5 held in the opening 3; a strip of metal 6 is secured to the bottom of the other depression or recess, and holds in the opening 3 co-operating extension 7. This

extension 7 may be provided with a contact point similar to contact point 5, but such contact point I find is not always necessary. The depressions 2 carry the covers or caps 8, forced into these depressions, which they fit snugly, and holding in place the element 4 and the strip or member 6. This element 4 and strip 6 have lateral projections 9 and 10 respectively as illustrated specifically in Figures 2, 3, and 4. These projections enter corresponding lateral recesses or slots 9' and 10' in the insulating body 1, on each side of the opening 3, at both ends of this opening; see Figure 5. The element 4 and the strip 6 each have moreover a tongue 11 with an extension 12. The object of the tongue 11 is to engage the caps 8 and make firm contact therewith, and the object of the extension 12 is to wedge in between the cap 8 and the side of the depression 2 and to assure more definitely that a good electrical contact is established. Surrounding the element 4 is a heater wire 13 insulated from the strip by a wrapping 14 of heat resisting material such as asbestos. In Figure 4 the element of bimetallic material 4 is illustrated in a developed form such as it appears when it is punched out from stock, and made as a stamping. It will be seen that this piece will be bent along the lines 15 in such a way that the part carrying the lateral projections 9 and 10 is at right angles to the body of the element 4 and strip 6 and the tongue 11 parallel to the same, while the narrow extension 12 again is at right angles to fit the side of the depression 2.

In practice the contacts 5 and 7 will be normally separated but current flowing through the heater member 13 will cause the element 4 to grow warm and bend in such a way that contact 5 goes into engagement with extension 7. One end of the wire 13 is attached to the element 4 while the other end is wedged under the lower cap 8 in electrical engagement with strip 6 bearing extension 7. Therefore, when the contacts 5 and 7 touch, the wire 13 is short-circuited and the current ceases to flow in it. The cooling of the wire enables the element 4 to resume its original position and separate the contacts.

This process will continue indefinitely, giving the intermittent operation or flashing of the electrical devices in the circuit of this device.

In the alternative arrangement according

to Figure 6, the insulating body or base 1 is supplied besides the two depressions 32 and the opening 33 with two round holes 17 and 18 on either side of the first opening and the 5 depression 32 on one side only has an extension 20 which surrounds the hole 17. The element 4 and the strip 6 are mounted in the sides of the opening 33, into corresponding slots. The element 4 has a connecting piece 10 of metal 19 bent as illustrated in Figures 6, 7, and 8, to fit into the opening 17 and project to the under side of the same.

Over one side of this opening 17 is an insulating cover 21 and the metal cover 22 holds 15 this insulating cover in position. The cover 22 also closes the opening 33 from one side, while an insulating cover 23 covers the same opening from the other side.

In this construction, which may be used 20 for lamp sockets which have two projecting prongs for making contact, one of these prongs will make a connection through the hole 18, while the other prong will make connection to the extension 19 through the heater 25 wire 13 to strip 6, which is in electrical connection with cover 22. The part of cover 22 under the hole 17 will then make connection with the circuit terminal of the lamp base, since it is placed exactly at the point where 30 the prongs should have been. In this way a complete connection will be established through the heater wire 13 and when this wire heats the element 4, the latter will bend to make contact between contact 5 and the 35 corresponding contact 5', thus short-circuiting the heater wire and allowing it to cool. This process will continue indefinitely, giving the intermittent operation or flashing of the electrical device in the circuit of this 40 device.

It will be seen that the manufacture of this device includes only simple molding operations, punching operations, and assembly of parts, except riveting of the contacts on the 45 element 4 and strip 6 and the winding of wire 14. Thus, a device which is simple and inexpensive to manufacture, but which gives satisfactory operation in practice, is secured.

Having described my invention, what I believe to be new and desire to secure and pro-

tect by Letters Patent of the United States is—

1. In a disk-shaped flasher for an electrical circuit a thermally responsive element, a co-operating member, a heater member, an insulating support for said element and said co-operating member, the support having slots therein to be engaged by said thermally responsive element and the co-operating member. 55

2. In a disk-shaped flasher to fit an electrical socket a thermally responsive element, a co-operating member, a heater member and a formed insulating support for said members and said element, the said insulating support 65 having slots therein, the element and the co-operating member having projections to enter the slots and bearing contact surfaces to move into and out of engagement with each other.

3. In a flasher for an electrical circuit 70 comprising an insulator body with openings, one of said openings provided with slots, a thermally responsive element and a co-operating member engaged by said slots, a contact making cover on one side of said opening, 75 and an extension on said contact making cover to cover one of the other openings.

4. In a flasher for an electrical circuit comprising an insulator body with openings, one of said openings provided with slots, a thermally responsive element and a co-operating member engaged by said slots, a contact making cover on one side of said opening, and an extension on said contact making cover to cover one of the other openings, and an electrical connection joined to said thermally responsive element and insulated from said first extension. 80

5. In a flasher for an electrical circuit comprising an insulator body with openings, one of said openings provided with slots, a thermally responsive element and a co-operating member engaged by said slots, a cover on one side of said opening, and an extension on said cover to cover one of the other openings, and an insulating cover on the other side of said first opening. 85

In testimony whereof I have affixed my signature.

WILLIAM DUBILIER.
